United States Patent Office

Des. 205,240
Patented July 12, 1966

205,240

DOOR LIGHT

Ralph D. Needham, 2221 Otley Ave., Perry, Iowa

Filed Aug. 25, 1965, Ser. No. 86,712

Term of patent 3½ years

(Cl. D48—20)

I claim:

The ornamental design for a door light, substantially as shown.
